TELESCOPING DOOR

Roger Garcia, Jackson Heights, N. Y.

Application April 10, 1950, Serial No. 154,915

4 Claims. (Cl. 160—196)

1

This invention comprises novel and useful improvements in a telescoping door and more generally pertains to a telescoping slidable partition equally adapted to forming a door, a wall or other partition.

The principal object of this invention is to provide an improved telescoping slidable door construction which may be readily telescoped and stored in a compact arrangement, or may be easily extended to form a partition, door or other closure.

A further important object of the invention is to provide an improved telescoping door in conformity with the preceding object, wherein the telescoping sections are slidably supported at their upper ends and are movable longitudinally and horizontally along their support members.

Yet another important object of the invention is to provide an improved construction of sliding door wherein the various panel sections of the same are connected to each other in an improved manner to permit but limit relative sliding movement between the sections from their telescoped or stored position in their expanded or operative position.

Still another important object of the invention is to provide an improved construction of sliding door as set forth in the preceding object, wherein the connecting linkage is housed within the telescoping panel sections of the door.

And a final important object of the invention to be specifically enumerated herein, resides in the provision of a telescoping door in conformity with the foregoing objects wherein all of the panel sections of the door except the end section are formed by spaced side walls, together with a common means securing the side walls in spaced position with respect to each other and pivotally connecting the linkage to each of the panel sections.

These, together with various ancillary features and objects of the invention, which will later become apparent as the following description proceeds, are attained by the present invention, a preferred embodiment of which has been illustrated, by way of example, in the accompanying drawings, wherein:

Figure 1 is a fragmentary front elevational view showing a door construction embodying the principle of this invention, the improved door being shown in its closed position;

Figure 2 is a vertical transverse sectional view taken substantially upon the plane indicated by the section line 2—2 of Figure 1, parts being broken away;

2

Figure 3 is a vertical longitudinal sectional view through the construction of Figure 2, showing the relation of the connecting linkage to panel sections of the door, the elements being shown in the expanded or door closing position;

Figure 4 is a horizontal sectional view taken substantially upon the plane indicated by the section line 4—4 of Figure 3, the telescoping panel sections of the door halves being shown in full lines in their closed position and in the dotted lines in their extended position;

Figure 5 is a horizontal sectional view taken substantially upon the plane indicated by the section line 5—5 of Figure 3 and showing the connecting linkage and the door panels in the expanded position of the door construction; and,

Figure 6 is a vertical transverse sectional detail view taken substantially upon the plane indicated by the section line 6—6 of Figure 3, and illustrating certain structural details of the linkage and its connection with the door panels.

Referring now more specifically to the accompanying drawings, wherein like numerals designate similar parts throughout the various views, attention is directed first to Figure 1 wherein there is disclosed a door construction consisting of a pair of telescoping or slidable doors, which are associated with a doorway opening to form a closure therefor, each of the two door halves being of identical construction, so that the illustration and description of one will be deemed sufficient for the construction of both.

Referring now more specifically to Figures 2—5, it will be seen that the door framing includes vertical members 10 having a horizontal cap member 12 extending across the upper ends or between the upper ends of the same. Secured to each of the members 10 and beneath the cap member 12, is a housing for storing the telescoped panel sections of each of the sliding door halves. As shown best in Figures 3, 4 and 5, each of these housings includes a vertical frame member 14 which is secured against the base of the member 10 in any desired manner, and a pair of side members 16 which embrace the opposite sides of the member 14, and extend inwardly from the member 10 into the door opening towards each other being open at their inner ends. Extending across the entire width of the door opening between the members 14, are top members 18 which overlie the members 14, and bottom members 20 which lie between the

members 14 at their lower ends. The members 14, 18 and 20 thus constitute the framing for the door.

As will be more readily apparent from Figures 2 and 3, a rigid horizontal supporting member 22, in the form of a bar or pipe, is seated in the members 14 adjacent their upper ends, and constitutes a rigid horizontal supporting member as set forth hereinafter. A cable or the like 24 is likewise positioned between the members 14 and above the horizontal supporting member 22, being entrained over supporting pins 26, or rollers 28 provided thereon. The cable 24 is tightly drawn between the two members 14, being fixedly secured to the end panels 30, and constitutes a flexible horizontal cable whereby the two door sections may be simultaneously operated.

For an understanding of the construction of the telescoping door, attention is now directed more specifically to Figures 4 and 5, wherein it will be seen that each door half consists of an end door panel 30 the same including an inner panel member 32 encased in a pair of parallel side panel members 34, the inner member 32 being notched or cut away what may be termed its rear end to provide a recess 36, as shown best in Figure 3. The recess is employed for attaching to the end panel 30 a parallel bar connecting linkage as set forth hereinafter.

In addition to the end panel 30 previously described, each door half further includes other panel sections 38, 40 and 42, each of which comprises spaced parallel walls 44, 46 and 48 respectively. These side walls are secured together in fixed relation by a means to be hereinafter set forth, so that the panel section 40 constituting the rear panel of the door assembly is slidably received between the housing side wall 16, the next panel section 42, the section 38 being slidably received in the section 42, the section 38 being slidably received in the section 40, while the end panel 30 is slidably received within the panel 38.

The arrangement is such that the panel sections of the door may be selectively disposed in their telescoped or retracted position, as shown in full lines in Figure 4; thereby permitting free opening of the space between the doorway post 14 between the ends of the housing wall 16. However, the door may be opened into the full line position shown in Figure 5, or the dotted line position shown in Figure 4, so as to close the door opening. It will be readily understood that the size of the panel sections may be such that one telescoping door panel assembly will be sufficient to close the entire door opening, although it is preferred to provide for large door openings the arrangement shown in Figure 1, wherein the end panels 30 of two door halves meet at the middle of the opening and in endwise abutting engagement as shown clearly in Figures 1 and 3.

Reference is now made more particularly to Figure 2 where it will be seen that the door sill 20 is provided with a central rib 50 of sufficient width to underlie and constitute a door sill for the lower edge of the end panels 30, although it is not intended that these end panels shall rest upon the member 50, but shall be supported for movement slightly above the same. In addition, the door sill 20 is provided with lateral shoulders 52 which are horizontally and longitudinally disposed on opposite sides of the portion 50, and which in turn serve as door sills for the lower edges of the side walls 44 of the panel sections 38. The lower edges of the side walls 46 and 48 of the panels 40 and 42, as shown

in Figure 2 are disposed in the same horizontal plane and on opposite sides of the member 20.

The end panels 30 are directly mounted upon and slideable upon the rigid supporting member 22 and for this purpose are provided with notches or recesses 54 in the upper edge of the member 32, for the reception of upper and lower sets of transverse axles 56 and 58, which are provided with guide rollers 60 and 62, which respectively rest upon the upper and lower surfaces of the member 22, for supporting the weight of the end sections 30 thereon and for guiding the same during transverse movement of the end sections. At their upper forward ends, each of the side walls of the other panel sections 38, 40, and 42 are connected by transversely disposed pins 64. As shown in Figure 3 these pins also serve to guide and tension cable 24; however, this function, although a desirable one, could be eliminated without departing from the spirit of the invention. Adjacent their upper and lower rear edges, the side walls of each of the panel sections 38, 40 and 42 are rigidly connected to each other and in spaced relation as by transversely disposed rods or bolts 66. The position of the bolts 66, and the pins 64 is such as not to interfere with the nesting of the telescoping sections in their collapsed or stored position.

A connecting parallel bar linkage is provided for securing the various sections of each of the door assemblies together, and for permitting but limiting relative telescoping movement between the panel sections. For this purpose, as shown best in Figures 3 and 5, a vertical or longitudinal slot 68 is disposed in the housing member 14 this slot being preferably substantially identical with and complementary to the previously described slot 36 in the end panels 30. A plurality of transversely disposed pins 70 are fixedly secured in any desired manner in the member 14 and extending across the slot 68 to constitute axles or pivot pins for the connecting bar linkage. Similarly, pins or axles 72 are secured between the side walls of the slot 36 and the end panel 30 in substantially the same horizontal planes with the pins 70, these pins 72 being retained as by fastening screws 74 extending through the panels 34 of the end panel 30.

Pivoted secured to the intermediate pin 70, in properly spaced relation thereon as by spacer washers or the like 76, are a pair of parallel bar links 78 and 80, each comprising a pair of links. At their opposite ends, the links 78 and 80 are pivotally connected at 82 and 84 respectively with the ends of a longer pair of links 86 and 88 respectively. The other extremities of the links 86 and 88, are respectively pivoted to the upper and lowermost of the pivot pins 72 in the slot 36. For this purpose, the links 86 and 88 are provided with elongated slots 90 and 92 respectively which thus have a sliding or lost motion upon the pins 72.

In a similar manner, a pair of links 94 and 96 are likewise pivoted to the central pivot pin 72 of the end panel 30, and at their other ends are terminally pivoted at 98 and 100 to the ends of levers 102 and 104, whose other extremities are connected as by the elongated slots 106 and 108 to the upper and lower pins 70.

It will be here noted that the links 78, 80, 94 and 96 are of equal length, and are shorter than the links 86, 88, 102 and 104 which are of equal length.

It will thus be seen that a parallel bar linkage connects the end panel 30 with the door post

14 for limited relative sliding movement with respect thereto.

Link 78 is pivotally connected to link 104 at 110, while link 80 is similarly connected to link 102 at 112. In turn, link 94 is pivotally connected at 114 with the link 88, while link 96 is pivoted at 116 to the link 86.

A pair of transverse links 118 and 120 are secured to each other at their midpoint by a pivot 122, and on opposite sides of pivot 122 are respectively pivoted at 124, 126 to the links 102 and 88; and at 128 and 130 are pivoted to the links 104 and 86. The links 86, 88 in turn are pivoted to each other at 132, while links 102 and 104 are pivotally connected at 134.

The opposite ends of the link 120 are slotted at 136 and 138 and are pivotally connected at 140 and 142 to corresponding slots 144 and 146 formed in the links 80 and 94. In a similar manner the link 118 is provided with terminal slots 148 and 150 pivotally connected at 152 and 154 to corresponding slots 156 and 158 in the links 78 and 96. Intermediate their ends, the links 86 and 102 are provided with registering slots 160, 162, pivotally connected to each other as by a pivot pin 164, while the links 88 and 104 in turn are provided with longitudinal slots 166 and 168 pivotally connected to each other as at 170.

At this point it should be noted that the pivot pins 132, 122, 134, not only serve to pivotally connect certain of the links together, but also constitute fastening and spacing means for the side walls of the panel sections 38, 40 and 42. For this purpose, as more readily apparent from Figure 5, each of the pivot pins includes a shaft 172, which extends between the side walls of the associated panel sections and fixes the space therebetween and is internally threaded at its opposite extremities for attachment to the panel side walls as by bolts 174. Suitable spacing collars 176 are provided loosely upon the shafts 172 between the side walls of the associated panel sections for maintaining the links pivoted thereon in proper relation. As will be further apparent from Figure 5, the links of the shafts 172 and in the spacing sleeves 176 of the various panel sections will vary with the widths of these sections.

In a similar manner, each of the pivot pins 140, 170, 154, 152, 164 and 142 likewise constitute combined pivot pins for the links and fastening and spacing members for the side walls of the panel sections. As shown in Figure 6, the construction of these combined pivot pins and spacing and fastening members is identical with that described in connection with Figure 5.

From the foregoing, it is felt that the operation of the parallel connecting bar linkage will now be readily understood. The linkage will maintain the various sections of the door in proper relation to each other during movement from the collapsed to the extended position, and it is observed that the connecting bar linkage is compactly housed within the telescoping sections themselves.

From the foregoing, the construction and operation of the device will be readily understood and further explanation is believed to be unnecessary. However, since numerous modifications and changes will readily occur to those skilled in the art after consideration of the foregoing specification and accompanying drawings, it is not desired to limit the invention to the exact construction shown and described, but

all suitable modifications and equivalents may be resorted to, falling within the scope of the appended claims.

Having described the invention, what is claimed as new is:

1. A telescoping door assembly comprising a supporting frame including at least one vertical support member, upper and lower horizontal support members extending from and having one of their ends secured to said vertical support member, a plurality of telescoping panel sections disposed within said supporting frame, said panel sections including an end panel section remote from said vertical support member and a plurality of intermediate panel sections extending from said vertical support member toward said end panel section, each of said intermediate panel sections having spaced side walls slidably embracing an adjacent panel section, said end panel section being slidably mounted at its upper and lower edges on the respective upper and lower horizontal support members, a parallel bar linkage connected at one end to said vertical support member and at its other end to said end panel, vertically spaced and horizontally aligned pins secured to the facing walls of said spaced side walls of said intermediate panel sections and maintaining them in spaced relation, link bars of said parallel bar linkage being pivoted on certain of said horizontally aligned pins and supporting said intermediate panels between said vertical support and said end panel, additional link bars being pivotally secured to the vertically spaced pins on opposite sides of said certain horizontally aligned pins, said additional link bars having slotted ends at their pivotal securing to provide a lost motion connection whereby said panel sections may be telescoped and expanded.
2. A telescoping door assembly comprising a plurality of telescoping panel sections and means supporting said sections, said panel sections including an end panel section and a plurality of intermediate panel sections extending from said end panel sections, each of said intermediate panel sections having spaced side walls slidably embracing an adjacent panel section, a parallel bar linkage connecting said sections together and permitting telescoping movement therebetween, vertically spaced and horizontally aligned pins secured to facing walls of said spaced side walls of said intermediate panel sections and maintaining them in spaced relation, link bars of said parallel bar linkage being pivoted on certain of said horizontally aligned pins, additional link bars being pivotally secured to the vertically spaced pins on opposite sides of said certain horizontally aligned pins, and said additional link bars having slotted ends at their pivotal securing to provide a lost motion connection whereby said panel sections may be telescoped and expanded.
3. A telescoping door comprising a horizontal support member and a vertical support member, a plurality of telescoping panel sections, means for mounting an end panel section upon said horizontal support member for sliding movement thereon, a parallel bar linkage connected to said vertical support member, each of said panel sections except said end panel section having spaced side walls slidably embracing an adjacent panel section, vertically spaced and horizontally aligned pins secured to facing walls of said spaced side walls of said panel sections and maintaining them in spaced relation, link bars of said parallel bar

linkage being pivoted on certain of said horizontally aligned pins, additional link bars being pivotally secured to the vertically spaced pins on opposite sides of said certain horizontally aligned pins, said additional link bars having slotted ends at their pivotal securing to provide a lost motion connection whereby said panel sections may be telescoped and expanded.

4. The combination of claim 2 including spacer sleeves on said pins interposed between said link bars and the facing side walls. 10

ROGER GARCIA.
